MECHANISM FOR ANGULAR ADJUSTMENT OF SURGICAL PIN AND NAIL DIRECTING APPARATUS IN A VERTICAL PLANE

Marion F. Stephens, Sullivan, Ind., assignor to
The Guidoscope Corporation, Chicago, Ill., a
corporation of Illinois

Original application January 22, 1945, Serial No.
573,954. Divided and this application October
14, 1948, Serial No. 54,425

5 Claims. (Cl. 128—92)

1

This invention relates to mechanism for angular adjustment of surgical pin and nail directing apparatus in a vertical plane, and comprises a division of my co-pending application Serial No. 573,954 entitled Post Adjusting Means for Wire and Nail Directing Apparatus, filed January 22, 1945 and now Patent No. 2,454,680, granted November 23, 1948.

As conducive to a clearer understanding of this invention it may be pointed out that in the extensive practice of hip nailing, there has been developed what is called the Smith-Peterson technique. It comprises the insertion of a guiding pin or wire in the shaft of the femur, the wire serving to guide a cannulated vitallium Smith-Peterson nail inserted in such a manner that it parallels and is in contact with the medial and anterior cortex of the neck of the femur. The guide, commonly called a Steinmann pin, is usually about three-thirty-seconds of an inch by ten inches and is removed from the bore of the nail after the latter has been properly positioned in the fractured neck of the femur. The Smith-Peterson nail for an adult is about five inches long and has a diameter of five-thirty-seconds of an inch although it is flanged and generally triangular in cross-section. It extends through a hole drilled in the hard outer portion of the femur, the hole extending in line with the center of the acetabulum at approximately 20° anterior angle. The nail extends through the neck and preferably into the head or ball-like portion of the hip joint, and its function is of course to reinforce the head on the neck of the femur. For the best results, the nail must be nearly in the direct weight-bearing line of the joint and so positioned that it receives the support of the dense corticle bone on both sides of the distal fragment. The insertion of both the guide pin and the nail must be controlled at all stages by two-plane radiography and in the past the successful placement of such fixation devices has depended largely upon the senses of sight and touch of the surgeon and has required a high degree of skill. As will be readily apparent various types of adjustment are needed for an apparatus of this character. Suitable means for rotary angular adjustment of the apparatus in a horizontal plane are described in my above mentioned patent.

2

A primary object of the instant invention is the provision of mechanism for angular adjustment in a vertical plane of the pin or nail guide of such a surgical instrument.

5 Another object is to provide an adjustable support for the nail guide which may be quickly set in an approximate adjustment and then further moved to obtain a finer adjustment.

The invention resides in the combinations of 10 elements, arrangements of parts, and features of construction, all as will be more fully pointed out in the accompanying drawing wherein there is disclosed a preferred embodiment of this inventive concept.

15 In the drawings:

Fig. 1 is a side elevational view of one form of device embodying the features of the present invention.

Fig. 2 is an end elevational view of the construction of Fig. 1, as viewed from the right.

Fig. 3 is a fragmentary view of a portion of Fig. 1 as viewed from the opposite side.

Fig. 4 is an enlarged sectional view taken substantially along the line 4—4 of Fig. 2 as viewed 20 in the direction indicated by the arrows.

Fig. 5 is an enlarged detail sectional view taken substantially along the line 5—5 of Fig. 2 as viewed in the direction indicated by the arrows, and

25 Fig. 6 is a reduced schematic view showing the relationship of mechanism comprising the instant invention with other portions of the apparatus.

Similar reference characters refer to similar 30 parts throughout the several views of the drawing.

Referring now to the drawings in detail and 35 particularly to Fig. 6, the apparatus or instrument comprises a base plate generally indicated 40 at 10 supporting a tubular member 11 within which is linearly movable a main post 12, a suitable operating wheel 13 being provided for vertical adjustment of the post in any desired manner, such, for example, as that set forth in my application Serial No. 54,424 filed concurrently herewith and entitled Mechanism for Vertical Adjustment of Surgical Pin and Nail Directing Apparatus. Rotary adjustment of the post is 45 provided by means of a spider 14 including an

operating nut 15 as disclosed in the above mentioned patent.

Referring now to the apparatus of the instant invention in detail, the upright post 12 is formed with a reduced and squared portion 15, the upper extremity of which is bifurcated to form bearing ears or brackets 16 (see Fig. 2). A shaft 19 having a square or flat-faced intermediate portion is rotatably mounted in said ears by providing them with bearing openings to receive cylindrical journal portions 17 and 18 formed at the ends of the squared portion. A depending shank 21 ears 16 and has at its lower end a square or flat-faced portion on a transversely extending guide for a surgical pin, nail, drill or the like, fits between a faced notch 20 to engage shaft 19 as seen in Fig. 5. Shank 21 is preferably secured to the shaft by a screw 21' which when removed permits the guide to be readily lifted off of the shaft.

The guide 22 is an elongated body extending transversely above the post and has in its top a V-shaped groove in which may be clamped a nut or the like by an inverted U-shaped spring clip or other means. These parts form no part of the present invention and are claimed in my application Serial No. 54,426 filed concurrently herewith and entitled Pin Guide and Securing Means for Surgical Nail and Pin Directing Apparatus.

It will be seen that when shaft 19 is turned the nail guide will be angled in a vertical plane. I provide means for indicating the angular adjustment of the guide and also means for permitting first a quick and approximate adjustment of it and then a finer adjustment. Between the shaft and the post I provide protraction means for indicating the adjustment. Preferably a protractor plate 27 has a hub portion 26 with a squared opening to receive a squared portion 25 formed on a portion of shaft 19 which extends beyond the journal portion 18. A nut 28 screwed on a reduced threaded extremity 29 of the shaft may be used to fasten the protractor to the shaft. The graduations on the protractor coat with a fixed mark 33 which is preferably on an arcuate plate 31 fastened by screws 32 to the post, as seen in Fig. 3. It is obvious that a vernier may be used in place of parts 31, 33.

The means for moving the shaft to obtain a fine adjustment after an approximate adjustment has been made and to lock the shaft against turning, is preferably located at the other end of the shaft and is associated with the journal portion 17. The latter, as seen in Fig. 4, extends beyond the associated ear or bracket 16 and has rotatably clamped upon it a collar or hub 35 carrying a flat and downwardly projecting radial arm 41. An internally threaded boss 36 on hub 35 carries a set screw 37 with a milled head 38. A cap screw 40 threaded in a socket in the end of the shaft retains the hub thereon. When screw 37 is turned in one direction it locks the arm to turn with the shaft. The arm 41 is actuated and then locked by a pair of axially aligned screws 42 provided at their outer ends with milled heads 43 and having their inner ends engageable with the opposite sides or faces of arm 41, as shown in Fig. 1. Screws 42 are engaged with screw threads 44 in nut members 45 carried by and spaced outwardly from the post. The nuts 45 may be formed integral with the post or on the ends of a transverse bar or plate 46 suitably secured to the post.

From the foregoing the operation of the mechanism should now be readily understandable. When it is desired to vary the vertical angular adjustment of guide 22 rotation of knob 38 will

release set screw 37, whereupon protractor 27 may be rotated, which rotation will, in turn, be imparted through shaft 19 to shank 21, and hence to guide member 22. Obviously a relatively fine adjustment may be made after initial setting, by suitable rotation of knobs 43 to vary the relative position of screws 42 and hence arm 41. When one screw 42 is backed away from the arm, the other may be turned to move the arm to the desired extent.

From the foregoing it will now be seen there is herein provided improved mechanism for the angular adjustment of a nail or pin guide in a vertical plane, which accomplishes all the objects of this invention and has many advantages.

I claim:

1. In a mechanism of the character described, a base, an upright post rising therefrom, a transverse shaft rotatably mounted at the upper end of said post, an elongated guide for a nail or the like fixed to an intermediate portion of said shaft and disposed above and extending transversely of said shaft, a protractor fixed to said shaft at one side of said post and coacting with a fixed mark carried by said post, a hub rotatably clamped to said shaft at the other side of said post and carrying a radial arm and a pair of axially aligned adjusting screws supported from said post and having their inner ends engageable with opposite faces of said arm.

2. The structure of claim 1 in which said post has a bifurcated upper end to provide bearing ears, said shaft has spaced cylindrical portions journaled in said ears and a flat-faced intermediate portion, and said guide has a flat-faced recess to engage said intermediate portion of the shaft.

3. In a mechanism of the character described, a base, an upright post rising therefrom, and having a bifurcated upper end forming spaced bearing ears, a transverse shaft having a square portion between spaced cylindrical journal portions, the latter being rotatable in said ears, an elongated guide for a nail or the like disposed transversely above said post and having a depending shank with a rectangular notch in its lower end for detachable engagement with the squared portion of said shaft, a hub rotatable on an outer end of one of said journal portions and carrying a radially extending arm, a set screw for clamping said hub to said one journal portion, spaced nut members carried by said post and disposed on opposite sides of said arm, opposed adjusting and clamping screws in said nut members with their inner ends engageable with opposite sides of said arm, and a protractor fixed to the other of said journal portions and coacting with a fixed mark carried by said post.

4. In a mechanism of the character described, an upright post, a transverse shaft rotatably mounted at the upper end of said post, an elongated guide for a nail or the like, said guide being disposed transversely above said post and fixed to said shaft to move therewith, a protractor fixed to said shaft and co-acting with a fixed mark carried by said post, a radial arm having one end adjustably fixed to said shaft, and a pair of axially aligned adjusting screws supported from said post and having their inner ends engageable with opposite faces of the free end portion of said arm.

5. In a mechanism of the character described, an upright supporting post, a transverse shaft rotatably mounted at the top of said post and carrying an elongated guide for a nail or the like,

said guide being disposed transversely above said post, means for effecting an approximate adjustment of said shaft and its guide, said means including a protractor fixed to said shaft and co-acting with a fixed mark carried by said post, and means for effecting a fine adjustment of said shaft and its guide, said last mentioned means including a radial arm having one end adjustably secured to said shaft and a pair of axially aligned adjusting screws supporting from said post and

having their inner ends engageable with opposite faces of the free end portion of said arm.

MARION F. STEPHENS.
